UNITED STATES PATENT OFFICE.

FRANK A. BULLINGTON, OF KANSAS CITY, MISSOURI, ASSIGNOR TO BULLINGTON MOTORS, OF KANSAS CITY, MISSOURI, A COMMON-LAW TRUST CONSISTING OF SOLOMON STODDARD, ERNEST E. HOWARD, AND FRANK A. BULLINGTON.

ROTARY INTERNAL-COMBUSTION ENGINE.

Application filed June 10, 1922. Serial No. 567,287.

To all whom it may concern:

Be it known that I, FRANK A. BULLINGTON, a citizen of the United States, residing at Kansas City, in the county of Jackson 5 and State of Missouri, have invented certain new and useful Improvements in Rotary Internal-Combustion Engines; and I do declare the following to be a full, clear, and exact description of the invention, such as 10 will enable others skilled in the art to which it appertains to make and use the same, reference being had to the accompanying drawings, and to the figures of reference marked thereon, which form a part of this 15 specification.

This invention relates to prime movers for generating power and particularly to a motor in which an expandible motive fluid is employed to impart motion to pistons 20 which rotate about a common axis.

The particular type of motor involved includes cooperating pistons progressively rotatable about the axis of the power shaft, one piston having relatively accelerating 25 movement with respect to the latter and the other having relatively retarded movement. The pistons, however, rotate within the stator so that first one and then the other becomes the accelerated piston.

The illustrated embodiment of the invention particularly relates to four cycle rotary combustion motors and the primary object of the invention is to provide means whereby each piston will accelerate and retard at substantially the same rate so that 30 there will be a uniform application of the power generated within the motor to the driven shaft or power shaft so as to eliminate the liability of variation in the angular speed of the driven shaft during its rotation, as would be the case where there were pronounced variations in the accelerating and retardation of the complementary pistons 35 between which the explosions take place.

My invention also contemplates means for connecting the pistons to the driven shaft of the motor by suitable linkage or mechanism which will control the movements of the pistons about a common axis so that 40 they will have relative movement to compress fuel charges to combustible pressures 45

and whereby the pistons will have alternate, substantially uniform accelerating and retarding rotative movements to insure uniform application of the expansive force of 55 the ignited charges applied to complementary pistons to thereby, through the linkage, rotate the driven shaft with uniform application of power as well as to insure balanced 60 rotative movement of the pistons.

It is an important feature of my invention that the linkage for connecting the pistons to the driven shaft have constant planetary movement about the axis of the driven shaft during the operating periods 65 of the motor so that there will be no stationary parts to receive the impacts of the exploded charges, the constantly rotating connecting linkage planetating about the axes of the pistons and the driven shaft will 70 absorb the impact of the exploded charges during their movement and during the time that there will be relative movement between the operating parts of the linkage so that a hammer blow or direct impacting 75 contact will not result as would be the case where a stationary cam, for example, was the guiding element about which pins or shafts of the link members moves or where a fixed gear received all of the force 80 of the exploded charges from a pinion tooth.

In the construction illustrated in this application gears are shown but these gears do not receive the full impact from the exploded charges; they receive, however, a resultant force of the exploded charges. Such impact is absorbed in the linkage, the gears being utilized merely as delivering the resultant working force or torque to the driven shaft of the motor and are important 85 parts in controlling the relative movements of the pistons and the resultant working forces delivered to the driven shaft.

It is further an important feature of this invention that the motor is made in a compact, well balanced manner, there being novel details of construction such as the bearings for sleeved shafts and the connections of the various parts to the driven shafts, which will be specifically described 90 hereinafter, reference being had to the accompanying drawings, in which 100

Fig. 1 is a view partly in section and partly in perspective of a motor constructed in accordance with my invention.

Fig. 2 is a sectional view on the line 2-2 of Fig. 3.

Fig. 3 is a sectional view on the line 3-3 of Fig. 2, and

Fig. 4 is a diagrammatic view of a modified form of motor.

10 The motor casing as distinct from the crank shaft casing consists of two members 1 and 2, which may be connected together to form a cylinder 3, concentric with the axis of the motor. The member 1 is provided with a bearing collar 4, through which a shaft for one of the rotors projects. The engine casing, or piston casing, more correctly speaking, is adapted to be fastened to a cylindrical crank case 5 through the 15 medium of suitable fastening devices, such as the bolts 6.

20 The crank case 5 is provided with feet 7 and 8 to be secured to a base or support and by reference to the drawings it will be observed that the crank case is concentric with the piston cylinder and, therefore, its axis is in line with the axis of the bearing 4 and it is provided with a bearing collar 4' in axial alignment with the collar 4. The collars 4 and 4', however, support different shafts, as will be presently explained.

25 Within the cylinder 3 are pistons carried by parallel, independently movable rotors or discs 9 and 10, on the periphery of each 35 of which are suitably disposed pistons 11. The rotor 9 is provided with an elongated shaft 15, one end of which is mounted in the bearing 4 and the other end of which is mounted in the bearing recess 16 of a 40 driven shaft 17, mounted in the bearing 4'. The rotor 10 is provided with a concentric but sleeved shaft 18, mounted to rotate about the shaft 15 on the bearings 19 and 20. There is another shaft 21 within the shaft 45 15, which has an angular end 22 in a corresponding recess in the driven shaft 17. The shaft 21 projects through the outer end of the shaft 15 and carries a pulley 23 by means of which a belt may be driven 50 for a fan circulating pump or other element to be driven. On the extreme outer end of the shaft 21 is a clutch member 24 by means of which the shaft 17 may be turned over in the usual way common to hand cranked engines, or a self-starter may be employed, if desired.

55 The shaft 17 is the driven shaft or power shaft of the motor and it receives its motion from the piston rotor shafts 15 and 18 through linkage which planetates about the axis of the motor and about the axis of the driven shaft 17.

60 The linkage is best shown in detail in Figs. 1, 2 and 3. There is a linkage carrier 65 operated from the power or driven shaft 17.

The arm or side wall 25 is rigid with the bearing end of the shaft 17 and it is connected by a web 26 to a similar wall 27 having a bearing collar 28 mounted to oscillate on the shaft 18 on the bearing 29.

70 Diametrically opposite the wall 25 is a crank arm 30, which really is part of the wall 25, the members 25 and 30 constituting a crank arm rigid with the shaft 17 intermediate its ends. The crank arm portion 75 30 co-operates with a similar portion 30', which is a continuation of the wall or arm member 27 and in spaced relation therewith by the web 26. The ends of the members 30 and 30' are provided with bearings 80 31 and 32 in which is a two-throw crank shaft 33, having crank pins 34 and 35 arranged at 180 degrees apart. The crank pins are connected to crank arms 36 and 37, rigid with the shafts 15 and 18 respectively, 85 these arms 36 and 37 being connected to the crank pins by links 38 and 39, the opposite ends of the arms 36 and 37 having counter weights 40 and 41 to balance them with respect to the links. The crank shaft 33 is 90 provided with diametrically opposite counter weights 42 and 43, as will be clearly apparent by reference to Fig. 3.

95 The linkage carrier is also provided with counter balance weights 44 and 45, diametrically opposite the points at which the crank shaft 33 is supported. The crank shaft 33 is provided at one end with a fly wheel 46 and at the other with a pinion gear 47 which may consist of a single herring bone gear 100 meshing with a corresponding gear 48, rigid with the crank shaft bearing 4' so that the gear 47 may rotate about its own axis and revolve about the axis of the gear 48 to roll 105 upon its teeth.

110 Attention is called to the fact that the pinion gear and stationary gear are arranged at a two-to-one ratio so that there will be two complete revolutions of the crank shaft 33 to each revolution of the driven shaft 17 so as to provide for the four cycle actions of the pistons for each revolution of the driven shaft 17.

115 Another important feature of this invention is that the connecting rods on one side of a plane to the crank shaft and motor axis and the piston crank pins to which the connecting rods or links are fastened are all in a plane parallel to the motor axis and in alignment to a plane parallel to the motor axis of dead center position, which is the beginning at the piston stroke. The purpose of this arrangement is to make possible the dead center arrangement shown and to provide a piston movement which is practically a uniform accelerated and retarded movement of the respective pairs of pistons.

120 In Fig. 4 I have shown a modified piston and crank arrangement in which the mechanism is designed for three pairs of pistons 125

controlled by a crank shaft having three throws or crank pins equally spaced about the crank shaft center. In other words, the crank pins are 120 degrees apart. In this construction the gear ratio will be two-to-one, or substantially like that shown in the preferred form.

In this form 15' designates the inner piston shaft, 18' the intermediate piston shaft, 10 and 49 the outer piston shaft. The piston shaft 15', through its rotor, carries pistons 50 and 51; the shaft 18', through its rotor, carries pistons 52 and 53, and the shaft 49, through its rotor, is connected to pistons 54 15 and 55. The shafts 15', 18' and 49 carry cranks or arms 15'', 56 and 57 respectively, which are connected to the cranks 58, 59 and 60 of the crank shaft 33' through connecting rods or links 61, 62 and 63.

20 In the diagram in Fig. 4 the pistons are moving in a contra-clockwise direction. The pistons 52 and 54 are shown at the end of the compression stroke and ready to fire; the piston 50 is about midway of its expansion stroke; piston 55 is in position to permit exhaust between pistons 50 and 53; the space between 55 and 53 is being scavenged; a charge is being drawn in between pistons 51 and 55, and a charge is being compressed between 51 and 54.

It will be noted that at the dead center position, which is the beginning of the piston stroke with the charge compressed between pistons 52 and 54 and ready to fire 35 so as to impart a working stroke to the pistons 52 and 54, the piston cranks 56 and 57 with their pins and the crank pins 59 and 60 and the connecting rods 62 and 63, are all in alignment in the dead center position and 40 that as the crank shaft revolves from this position in a plane parallel to the motor axis, the working stroke between pistons 52 and 54 will be accomplished.

It will be noted that in the position described, piston 50 is advancing under a working stroke from a previous explosion, and that, through its crank arm 15'' and connecting link 61 to crank pin 58 of the crank shaft, is imparting a rotating force 50 to the crank shaft when the other crank pins and pistons are in dead center relationship. It will also be noted that piston 51 is performing a compression stroke for a succeeding charge.

55 It will be apparent that with the construction shown in Fig. 4 there will be six working strokes per revolution of the driven shaft, as distinct from four in the construction shown in Figs. 1 to 3. However, in other respects, the same generic principles embodied in the preferred form are carried out in the form shown in Fig. 4.

What I claim and desire to secure by Letters Patent is:

65 1. In a rotary four cycle combustion

motor, a cylindrical casing, pairs of pistons therein rotating about a common axis having relative movement to compress fuel charges to combustible pressures, means for igniting the compressed charges, a driven shaft, and mechanism for connecting the pistons to the driven shaft comprising a carrier rotatable with the driven shaft, a crank shaft mounted in said carrier, connecting rods on the crank pins of the crank shaft 70 and eccentrics connecting the connecting rods to the pistons, said eccentrics and connecting rods being disposed on one side of a plane passing through the axis of the crank shaft and through the axis of the 75 motor.

2. In a rotary four cycle combustion motor, a cylindrical casing, pairs of pistons therein rotating about a common axis having relative movement to compress fuel 80 charges to combustible pressures, means for igniting the compressed charges, a driven shaft, and mechanism for connecting the pistons to the driven shaft comprising a carrier rotatable with the driven shaft, a crank shaft mounted in said carrier, connecting rods on the crank pins of the crank shaft 85 and eccentrics connecting the connecting rods to the pistons, the eccentrics, crank pins, crank shaft and connecting rods being in alignment in a plane passing through the crank shaft axis parallel with the axis of the 90 motor at dead center position.

3. In a rotary four cycle combustion motor, a cylindrical casing, pairs of pistons 95 therein rotating about a common axis having relative movement to compress fuel charges to combustible pressures, means for igniting the compressed charges, a driven shaft, and mechanism for connecting the pistons to the driven shaft comprising a carrier rotatable with the driven shaft, a crank shaft mounted in said carrier, connecting rods on the crank pins of the crank shaft and eccentrics connecting the connecting rods to the 100 pistons, said eccentrics and connecting rods being disposed on one side of a plane passing through the crank shaft and motor axis, the piston eccentrics, crank pins, crank shaft, and connecting rods being in alignment in 105 a plane passing through the crank shaft axis parallel with the axis of the motor at dead center position.

4. In a rotary four cycle combustion motor, a cylindrical casing, pairs of pistons 110 therein rotating about a common axis having relative movement to compress fuel charges to combustible pressures, means for igniting the compressed charges, a driven shaft, and mechanism for connecting the pistons to the driven shaft comprising a carrier rotatable with the driven shaft having aligning crank 115 shaft bearings in spaced relation, a crank shaft mounted in said bearings and having cranks in the space between the bearings, 120 125 130

levers rotatable with the pistons, connecting rods connecting the levers to the cranks of the crank shaft, counter weights on the levers diametrically opposite the points at which they are connected to the connecting rods, and a counterbalance weight on the carrier diametrically opposite the crank shaft.

5. In a rotary four cycle combustion motor, a cylindrical casing, pairs of pistons 10 therein rotating about a common axis having relative movement to compress fuel charges to combustible pressures, means for igniting the compressed charges, a driven shaft, and mechanism for connecting the pistons to the

15 driven shaft comprising a carrier rotatable with the driven shaft having aligning crank shaft bearings in spaced relation, a crank shaft mounted in said bearings and having cranks in the space between the bearings, levers rotatable with the pistons, connecting rods connecting the levers to the cranks of the crank shaft, counter weights on the levers diametrically opposite the points at which they are connected to the connecting rods, a counterbalance weight on the carrier diametrically opposite the crank shaft, and a fly wheel on the crank shaft.

6. In a rotary four cycle combustion motor, a cylindrical casing, pairs of pistons 30 therein rotating about a common axis having relative movement to compress fuel charges to combustible pressures, means for igniting the compressed charges, a driven shaft, and mechanism for connecting the pistons to the driven shaft comprising a carrier rotatable with the driven shaft having aligning

crank shaft bearings in spaced relation, a crank shaft mounted in said bearings and having cranks in the space between the bearings, levers rotatable with the pistons, connecting rods connecting the levers to the cranks of the crank shaft, counter weights on the levers diametrically opposite the points at which they are connected to the connecting rods, a counterbalance weight on the carrier diametrically opposite the crank shaft, a fly wheel on the crank shaft, a rigid gear, and a gear on the end of the crank shaft distant from the fly wheel and rigid with the meshing gear.

7. A motor comprising a casing having a circumferential cylinder, rotors in the casing having pistons in the cylinder, a shaft having a short end projecting from one side of one rotor and a long end projecting from the other side of said rotor, a shaft on the complementary rotor projecting from one side only and sleeved on the long end of the first named shaft, a third shaft in axial alignment with the first two shafts and having a recess 60 to provide a bearing for the long end of the first-named shaft, a bearing in the casing for the short end of the first-named shaft, driving connections between the first two shafts and the third shaft, and a fourth 65 shaft projecting through the axial center of the first-named shaft and having positive engagement with the driven shaft, one end of the fourth shaft extending beyond the short end of the first shaft.

In testimony whereof I affix my signature.
FRANK A. BULLINGTON.
